No. 895,972.

PATENTED AUG. 11, 1908.

J. C. DANA.
ARTIST'S WORK REST OR HOLDER.
APPLICATION FILED MAY 12, 1908.

UNITED STATES PATENT OFFICE.

JOSEPH C. DANA, OF CONCORD, MASSACHUSETTS.

ARTIST'S WORK REST OR HOLDER.

No. 895,972.

Specification of Letters Patent.

Patented Aug. 11, 1908.

Application filed May 12, 1908. Serial No. 432,498.

To all whom it may concern:

Be it known that I, JOSEPH C. DANA, at present residing at Concord, in the county of Middlesex and State of Massachusetts, have 5 invented a new and Improved Artist's Work Rest or Holder, of which the following is a specification.

This invention is in the nature of an appliance, which, though more especially adapted 10 for artists' or draftsmen's uses, is also adapted for use as a book rest, and the said invention has for its object to provide an appliance of the character stated, of a simple and economical construction, in which the parts are 15 especially designed for conveniently supporting the artist's canvas, drawing board or other object on which he may desire to work, and for sustaining the brushes, pencils and other paraphernalia adjacent the work, 20 for convenient handling, and for being quickly stored in a compact manner when the appliance is not to be used.

In its subordinate features, my invention comprises a vertically adjustable stand or 25 supporting leg, a special form of table mounted on the upper end of the stand having drawers, slidably into the opposite ends thereof, one of the drawers having compartments for receiving different articles, such as 30 ink, pencils, a hinged cover for the said drawer, having means for conveniently sustaining the brushes, the paint tubes, etc. in a substantially vertical position adjacent one end of the table when it is raised up, means 35 being also included in the construction of the said drawer for supporting the brushes in their proper positions on the hinged member when the latter is closed down and the drawer is shoved in under the table, other 40 means in the nature of a rest or support hinged to the front end of the table that forms the work support, and which is disposed at right angles to the end drawers, and that is combined with a rack mechanism, 45 and a sustaining bail mounted on the table that engages rack members on the hinged member for holding the said hinged member to its adjusted positions.

In its still more subordinate features, my 50 invention consists in certain details of construction and peculiar combination of parts, all of which will be hereinafter fully explained, specifically pointed out in the appended claims and illustrated in the accompanying drawing, in which:—

Figure 1, is a perspective view of my in-

vention, the several parts being adjusted for use. Fig. 2, is a longitudinal section on the line 2—2 on Fig. 3 of the table with the drawers thereof closed, the easel or hinged holder being shown elevated. Fig. 3, is a cross section of the table and easel on the line 3—3 on Fig. 2, and Fig. 4, is a detail view of the easel and bail and rack devices, hereinafter referred to. Fig. 5, is a detail perspective view of an improved supplementary study holder.

In the practical arrangement, my invention embodies a tripod form of base *a* from which rises a hollow standard *a'* that receives 70 the pendent leg or rod *b*, and which is adjustably held in the standard by the clamp screw *b'*, see Fig. 2. On the upper end of the rod *b* is clamped a table or top member *C* to which the front and rear pendent members *c'*—*c*² 75 are secured and which are joined by the cross pieces *c*³—*c*³—*c*³ that form the supports for the drawers 1 and 2 that slide at the opposite ends under the table, see Fig. 2.

The drawer 1 is of the ordinary type, is located preferably at the left hand end of the table (see Fig. 1) and it preferably has one or more compartments 10 for holding ink or other articles. The other drawer 2 has a hinged top 20, that folds down, covers the 85 drawer, and to slide under the top *C*; it also has its hinged end 20 arranged to rest against a cross cleat 21 on the outer upper edge of the drawer so that when swung up, the said top 20 will rest in a vertical position, see Fig. 1 90 with its under face disposed convenient to the artist; and for sustaining the brushes and paint tubes, the said under side of the top 20 has side cleats 20^a, the lower ends of which join with a cross cleat or rest member 20^b 95 that has a series of apertures 20^a for receiving the brush handles 22, the said member 20^b also forming a convenient rest for paint tubes and other small artists' accessories.

For holding the brushes from dropping 100 down onto the bottom of the drawer when the top 20 is closed down, a wire bail piece 23 is secured to the bottom of the said drawer crosswise thereof, upon which the upper ends of the brushes rest as shown by dotted lines 105 on Fig. 2.

Combined with the means for conveniently holding the artists' brushes and other accessories, is an easel or holder 3 that consists of a rectangular frame hinged at 30 to a cleat 31 110 secured on the front upper edge of the table 2, the lower or hinged end of the frame having a

ledge or rest member 32 for supporting a canvas, board or other article on which the artist or draftsman works. For holding the said frame 30 at any of the desired angles the opposite ends thereof each has a pendent rack piece 40—40 and a guard bail 41 that co-operates therewith.

Co-acting with the racks 40 and the bails 41 is a Γ -shaped bail 5 hinged at its ends 50—50 to the opposite edges of the table, see 50^a, Figs. 2 and 4, and this bail piece engages with the racks 40—40, it being held from falling back and out of a close relation with the racks by the bails 41, which also serve to hold 15 the bail 50 in convenient position at all times for readily adjusting the pitch or angle of the easel 3.

From the foregoing, taken in connection with the accompanying drawings, the complete construction and the advantages of my invention will be readily understood. The same forms a convenient artists' appliance in which the required accessories can be conveniently stored and brought in position for 25 use and the several parts constituting the appliance compactly folded or closed up.

Besides using my appliance for the purposes hereinbefore stated, I may transform it into a study holder, for holding stray sheets, 30 books and the like, by attaching a metal plate *d* which has a brace *e* bent down therefrom to rest against the edge of the swinging rack 3, when the slots *f* and *f'* have been fitted over the screw heads *g* on the rack 3, as 35 shown.

Owing to the direction of slant of the slot *f* and *f'*, a very tight connection between the holder *d* and rack 3 is possible after they have been fitted on the screws and pressed down.

40 Having thus described my invention, what I claim is:

1. An appliance of the character described, comprising a suitable support, a table mounted thereon, an easel or supporting frame hinged at one end to the front upper edge of the 45 table, means on the table that connects with the frame for supporting the frame at its tilted positions, a drawer slideable under the table at one end thereof, said drawer including a hinged top having a rack on its under 50 side for holding brushes and other articles.

2. In an appliance of the character described, a suitable support, a table mounted on the upper end thereof, a drawer slideable under one end of the table, said drawer including a hinged member adapted to be swung up and held at a vertical position when the drawer is pulled out, means on the under 55 side of the said hinged member for receiving one end of brushes, and means in the 60 drawer for sustaining the free ends of the brushes when the said hinged member is closed down to slide with the drawer under the table.

3. An apparatus of the character described, 65 comprising a support, a table mounted thereon, said table being of box-like form, an easel or supporting frame hinged at one end to the front upper edge of the table, means on the table that connects with the frame for 70 supporting the frame in its tilted positions, a pair of drawers slideable endwise into the box-like table to be inclosed thereby when in one position, one of said drawers having a supplemental lid attached thereto, and means 75 carried by the supplemental lid for holding articles within the drawer.

JOSEPH C. DANA.
